UNITED STATES PATENT OFFICE

153,071

DESIGN FOR A COMBINATION REFRIGERATOR, ELECTRIC HOT PLATE, AND WATER COOLER UNIT

Elmer A. Lundy, New York, N. Y.

Application August 28, 1947, Serial No. 141,104

Term of patent 14 years

(Cl. D67—3)

To all whom it may concern:

Be it known that I, Elmer A. Lundy, a citizen of the United States, residing at New York, in the county of New York and State of New York, have invented a new, original, and ornamental Design for a Combination Refrigerator, Electric Hot Plate, and Water Cooler Unit, of which the following is a specification, reference being had to the accompanying drawing, forming part thereof, and in which:

Fig. 1 is a perspective view of a combination refrigerator, electric hot plate, and water cooler unit, showing my new design; and

Fig. 2 is a top plan view thereof.

The other side of the unit, not shown, is substantially like the side shown.

I claim:

The ornamental design for a combination refrigerator, electric hot plate, and water cooler unit, as shown and described.

ELMER A. LUNDY.
